UNITED STATES PATENT OFFICE

JAMES G. BOSWELL, OF FREEPORT, TEXAS, ASSIGNOR OF ONE-HALF TO WALTER L. RUSS, OF FREEPORT, TEXAS

CORE TRAP OR RETAINER

Application filed May 10, 1928. Serial No. 276,714.

This invention relates to a core trap or retainer as used in connection with the drilling of oil, sulphur or other wells for obtaining the core or cores as samples.

5 It is particularly aimed to provide a structure in which the catcher or trap does not turn with the drill while obtaining a core, and it is further a particular object to provide a construction wherein fine particles will not 10 lodge behind operating parts to prevent the same from opening incidental to entrance or reception of the core.

The more specific objects and advantages will become apparent from a consideration 15 of the description following taken in connection with accompanying drawings illustrating an operative embodiment, and wherein:

Figure 1 is a vertical sectional view taken 20 centrally and longitudinally through the improved device and adjacent drilling equipment.

Figure 2 is a plan view of the improved device,

25 Figure 3 is an elevation thereof, and

Figure 4 is a front elevation of one of the spring leaves.

Referring specifically to the drawings, 10 designates a core drill head which is to be 30 taken as conventional, the same being provided with cutters as at 11 to which water is supplied as usual through channels 12. The head 10 is generally cylindrical and at its lower end is provided with a shoulder at 13. 35 Into its upper end, a core barrel 14 of conventional form is threaded as at 15. The head 10 is also provided with screw threads 16 for attachment as usual to well tubing. The core barrel 14 extends inwardly so as to 40 provide a shoulder 17 at its lower end opposite the shoulder 13.

Between the shoulders 13 and 17, my improved core catcher or trap generally designated 18 is loosely mounted.

45 Referring specifically to the trap, at both its upper and lower ends, it is provided with a guide and keeper ring 19. The rings 19 have heads 20 which are inwardly extended and provided with inclined or beveled surfaces 21. Skirts 22 extend from the edge 21.

Riveted or otherwise fastened to the skirts 22 as at 23 are anchor rings 24 which have inwardly offset flanges at 25 which provide shoulders or abutments as at 26.

Loosely mounted normally in abutment 55 with the shoulders 26 is a spacer sleeve or cylinder 27 which intimately engages the inner surfaces of the rings 24 inwardly of the shoulders 26.

Core retaining or engaging blades or fingers are shown at 28. The blades 28 are separate from each other and used in any desired number to provide an annular gripping body for the core. Each blade at each end has a hook 29 which is in engagement 60 with the adjacent flange 25 whereby the blades are held in assembled relation. The blades also are overlapped with respect to each other as particularly shown in Figure 2 and are generally arcuate to provide a central 65 constriction 29, a relatively long and flat curved portion 30 and a relatively shorter and more abruptly curved portion 31.

To accommodate the overlapping and arrangement of the blades 29, upper and lower 70 corners of one side of each of them are preferably notched or cut away as at 32. The blades are generally of rectangular form as shown in the elevation in Figure 4.

In use, as the drill advances, the core enters the cage or trap 18, engaging the constriction 29 and serving to spread the same, whereby the core is effectively gripped by the blades 29 since they are of spring metal. The expansion of such blades causes the trap 80 18 to extend and this is permissible due to the clearance between the shoulders 13 and 17, the space not being completely filled by the trap in the absence of a core. The blades 29 so overlap each other as to exclude particles 85 and foreign matter from sift ing therethrough and which would affect expansion of the trap. It will be realized also that the trap while freely mounted in the device does not turn incidental to its reception or engagement with 90 the core.

The spacer sleeve 27 prevents longitudinal collapse or distortion of the parts as the core and trap engage.

The spacer sleeve 27 may have various 100

openings 33 in its wall to permit application and fastening of the rivets 23 after the spring blades 28 and rings 19 and 24 are assembled.

Various changes may be resorted to provided they fall within the spirit and scope of the invention.

What is claimed is:—

1. A core retainer comprising ring members, spring blades each having a hook at each end engaging said members, said spring blades being resiliently constricted throughout their length to provide a constricted passage intermediate of their ends to engage a core.

15 2. A core retainer comprising ring members, spring blades having hooks engaging said members, said spring blades being resiliently constricted throughout their length to provide a constricted passageway intermediate of their ends to engage a core, and a guide and keeper ring disposed over the hooks and connected to the first mentioned rings.

25 3. A core retainer comprising ring members, spring blades having hooks engaging said members, said spring blades being resiliently constricted throughout their length to provide a constricted passageway intermediate of their ends to engage a core, a guide and keeper ring disposed over the hooks and 30 connected to the first mentioned rings, the first mentioned rings having shoulders, and a spacer member disposed between said shoulders.

35 4. A core retainer comprising end members having slots about the same, spring blades at opposite ends extending into said slots whereby they are mounted in place, said spring blades being resiliently constricted throughout their length to provide a constricted passageway intermediate of their 40 ends to engage a core.

In testimony whereof I affix my signature.

JAMES G. BOSWELL.
